COLLAPSIBLE GREETING CARD

John Philip Parrotta, 925 N. Burch Road,
Fort Lauderdale, Fla. 33304

Filed Jan. 10, 1974, Ser. No. 432,292

Term of patent 7 years

Int. Cl. D19—05

U.S. Cl. D19—1

FIG. 1 is a front perspective view of a collapsible greeting card showing my new design;

FIG. 2 is a top plan view thereof;

FIG. 3 is a side elevational view partially in cross-section taken along lines 3—3 of FIG. 2 and looking in the direction of the arrows;

FIG. 4 is rear elevational view partially in cross-section taken along lines 4—4 of FIG. 3 and looking in the direction of the arrows; and

FIG. 5 is a rear perspective view thereof showing the bottom and side opposite that shown in FIG. 1.

I claim:

The ornamental design for a collapsible greeting card, as shown and described.
